(57) **CLAIM**

The ornamental design for a plug for trailer wiring, as shown and described.

DESCRIPTION

FIG. 1 is a top, front and side perspective view of a plug for trailer wiring showing our new design;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a bottom plan view thereof; and,

FIG. 7 is a top plan view thereof.

The broken line portion of the figure drawings is included to show unclaimed subject matter only and forms no part of the claimed design.
